UNITED STATES PATENT OFFICE.

ORANGE S. STURTEVANT, OF ADRIAN, MICHIGAN, ASSIGNOR TO ADRIAN WIRE FENCE COMPANY, OF ADRIAN, MICHIGAN, A CORPORATION.

TIE FOR WIRE FENCING.

SPECIFICATION forming part of Letters Patent No. 781,970, dated February 7, 1905.

Application filed October 22, 1904. Serial No. 229,530.

To all whom it may concern:

Be it known that I, ORANGE S. STURTEVANT, a citizen of the United States, residing at Adrian, in the county of Lenawee, State of Michigan, have invented certain new and useful Improvements in Ties for Wire Fencing; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to a tie for wire fencing; and it consists in the construction and arrangement of parts hereinafter fully set forth, and pointed out particularly in the claims.

The object of the invention is to provide a tie for wire fencing of simple and compact formation wherein the arrangement is such as to enable the crossed wires of a wire fabric or fencing to be securely tied at the junction thereof.

The above object is attained by the structure illustrated in the accompanying drawings, in which—

Figures 1 and 2 are perspective views of a tie involving my invention, showing said tie in position upon the crossed strands of a wire fabric or fencing. Fig. 3 is an edge view in elevation. Fig. 4 is a similar view looking at the opposite edge. Fig. 5 is a plan view of one face of the tie. Fig. 6 is a plan view of the opposite face. Fig. 7 is an end elevation.

Referring to the characters of reference, 1 designates the strand-wire of the fabric, and 2 the transverse or stay wire. These wires, as is common in the art, are crimped at their point of crossing to prevent lateral displacement. The tie-wire which unites the crossed wires is formed, preferably, in the shape of a staple and by means of a plunger and suitable dies (not shown) which embrace the crossed wires is driven into position upon said wires in the form illustrated. The tying-staple is forced into the forming-dies with the legs thereof upon opposite sides of the strand-wire, and said legs are so directed by the dies as to cause them to pass in the rear of the stay-wire, the leg 3 of the staple being directed upwardly

across the strand-wire and the terminal thereof formed into a return-bend and directed toward the stay-wire, as shown at 4. The leg 5 of the staple after passing the stay-wire is also directed upwardly over the strand-wire 1 and lies contiguously parallel to the bent terminal 55 4 of leg 3, as shown at 6, the extreme end of leg 5 crossing the strand-wire obliquely beyond the bent terminal of leg 3 and having formed therein a spiral eye 7, which embraces the strand-wire and securely fastens the end of 6c leg 5 of the tie thereto, forming the complete tie, with the loop end 8 thereof lying across the strand-wire on the opposite side of the stay-wire to that occupied by the curved and hooked terminals. The end portion 4 of the 65 leg 3 which describes the return-bend is bent downwardly after crossing the strand-wire, so as to more closely embrace said wire, as clearly shown in Fig. 4, and causes it to lie more nearly parallel with the portion 6 of the leg 5. 70

This form of tie secures the terminals of the legs of the tying-staple in a manner to prevent a possible disengagement of the tie from the crossed wires and at the same time avoids any undue protrusion of said terminal portions.

Having thus fully set forth my invention, what I claim as new, and desire to secure by Letters Patent, is—

1. In a tie for wire fencing, the combination with the strand-wire and stay-wire crimped at their point of crossing, of a tie comprising a loop having one end crossing the face of the strand-wire at one side of the stay, legs passing in the rear of the stay, the terminal of one leg crossing the strand-wire and having a bent portion, the other leg lying contiguously parallel with the bent terminal of the first-mentioned leg, also crossing the strand-wire, and having an eye formed in the end thereof which embraces the strand-wire. 80

2. The combination with the intersecting strand and stay wires crimped at their point of crossing, of a tie-wire comprising a staple having its loop end crossing the strand-wire, 85 legs passing in the rear of the stay-wire, the terminal of one leg crossing the strand-wire beyond the stay-wire and having a return-bend 90

95

which partially embraces the strand-wire, a portion of the opposite leg lying parallel to the return-bend of the first leg, and crossing the strand-wire contiguous thereto, the end 5 of said last-mentioned leg having a spirally-formed eye therein which embraces the strand-wire.

3. The combination with the intersecting strand and stay wires crimped at their point 10 of crossing, of a tie-wire comprising a staple having its loop end crossing the strand-wire, legs passing in the rear of the stay-wire, the terminal of one leg crossing the strand-wire beyond the stay-wire, and having a bent por-

tion which partially embraces the strand-wire, 15 a part of the opposite leg of the staple lying approximately parallel to the bent portion of the first-mentioned leg and crossing the strand-wire obliquely adjacent thereto, the end of the last-mentioned leg being bent to embrace the 20 strand-wire.

In testimony whereof I sign this specification in the presence of two witnesses.

ORANGE S. STURTEVANT.
